UNITED STATES PATENT OFFICE

DIANE HUBERT, OF CHICAGO, ILLINOIS

DESIGN FOR A LADY'S DRESS

Application filed March 6, 1930. Serial No. 34,753. Term of patent 7 years.

To all whom it may concern:

Be it known that I, DIANE HUBERT, a citizen of the United States, residing at Chicago, in the county of Cook and State of Illinois, have invented a new, original, and ornamental Design for a Lady's Dress, of which the following is a specification, reference being had to the accompanying drawing forming a part thereof.

Fig. 1 is a front view of a lady's dress showing my new design draped on a figure which is indicated in dotted lines.

Fig. 2 is a back view of same.

I claim:

The ornamental design for a lady's dress substantially as shown.

DIANE HUBERT.
